(57) **CLAIM**

The ornamental design for a glass attachment system, substantially as shown and described.

DESCRIPTION

FIG. 1 is an isometric view of the front, top and left side of the glass attachment system showing the new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an isometric view of the front, top and right side of a first clip which forms a part of the glass attachment system, seen at the first and third clip positions in FIGS. 1-7, shown separately for ease of illustration;

FIG. 9 is an isometric view of the rear, top and left side thereof;

FIG. 10 is a front elevation view thereof;

FIG. 11 is a rear elevation view thereof;

FIG. 12 is a left side elevation view thereof;

FIG. 13 is a right-side elevation view thereof;

FIG. 14 is a top plan view thereof;

FIG. 15 is a bottom plan view thereof;

FIG. 16 is an isometric view of the front, top and right side a second clip which forms a part of the glass attachment system, seen at the second clip position in FIGS. 1-7, shown separately for ease of illustration;

FIG. 17 is an isometric view of the rear, bottom and left side view thereof;

FIG. 18 is a front elevation view thereof;

FIG. 19 is a rear elevation view thereof;

FIG. 20 is a left side elevation view thereof;

FIG. 21 is a right side view thereof;

FIG. 22 is a top plan view thereof;

FIG. 23 is a bottom plan view thereof;

FIG. 24 is an isometric view of the front, top and right side of a third clip which forms a part of the glass attachment system, seen at the third clip position in FIGS. 1-7, shown separately for ease of illustration;

FIG. 25 is an isometric view of the rear, bottom and left side view thereof;

FIG. 26 is a front elevation view thereof;

FIG. 27 is a rear elevation view thereof;

FIG. 28 is a left side elevation view thereof;

FIG. 29 is a right side view thereof;

FIG. 30 is a top plan view thereof; and,

FIG. 31 is a bottom plan view thereof.

The portions of the figures shown in broken lines are included to show the environment in which the glass attachment system is intended to be used and do not constitute part of the claimed invention.

(Continued)

The glass attachment system is shown with a symbolic break in its length. The appearance of any portion of the article between the break lines forms no part of the claimed design. The dot dash dot lines immediately adjacent to the shaded areas represent bounds of the claimed design.
